[57] CLAIM

The ornamental design for a teaching aid for children
learning algebraic numbers, as shown and described.

DESCRIPTION

FIG. 1 is a perspective view from the front, top, and left
side of a teaching aid for children learning algebraic
numbers showing my design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof (the right side being a
mirror image thereof); and,

FIG. 7 is a perspective view thereof, with the drawer in
open condition containing ball-like objects.

FIG. 1

FIG. 2

FIG. 3

FIG. 4

FIG. 5

FIG. 6

FIG. 7
